FIG. 1.

FIG. 2.

FIG. 3. 18, 11, 81.

UNITED STATES PATENT OFFICE.

WILLIAM S. JOHNSON, OF LOS ANGELES, CALIFORNIA.

ENGINE-STARTER.

1,001,277.

Specification of Letters Patent. Patented Aug. 22, 1911.

Application filed January 26, 1911. Serial No. 604,758.

To all whom it may concern:

Be it known that I, WILLIAM S. JOHNSON, a citizen of the United States, residing at Los Angeles, in the county of Los Angeles and State of California, have invented new and useful Improvements in Engine-Starters, of which the following is a specification.

This invention relates to an engine starter applicable to any engine which must be started from some exterior source, especially such engines as the internal combustion now used, and more particularly to such engines as in use on automobiles.

The invention will be illustrated and described as in use on an automobile, but it will be understood that I do not limit myself to such use, the invention being highly useful on motor boats and vehicles of all kinds.

One of the main objects of my invention is to provide a device by means of which the engine may be easily started by the driver from his position in the seat of the machine, which will prevent any "back-firing" from working injury to the driver, and which is always in condition for starting the engine when the engine is at rest and will automatically be thrown out of engagement when the engine is running.

The invention is embodied in a combination of ratchet mechanisms mounted directly on the engine shaft or on a shaft connected with the engine shaft, just as is deemed the most desirable. In the accompanying illustrations I have shown my starter mounted on the forward end of the engine shaft, as this is the most convenient position for a shaft drive car; but in cars where the engine is mounted beneath the car body and the driving shaft extends across the car frame, it may be desirable to place my starter on the transverse shaft. These and other arrangements may be made to suit. The ratchet mechanisms are so combined that the rotation of one member in the correct direction will cause the rotation of the engine shaft. When the engine shaft begins revolving, the ratchet mechanism is thrown out of engagement and all the parts except the one directly attached to the engine shaft will then remain stationary. Means are provided for stopping the backward rotation of the engine, but this means is also so arranged that it does not act con-

tinuously while the engine is running. The mechanism embodying these features will be more clearly understood from the following detailed description of a preferred form of my invention when taken together with the accompanying drawings, in which—

Figure 1 is a plan view of a portion of an automobile chassis, showing my invention in place. Fig. 2 is an enlarged longitudinal section of my device taken on line 2—2 of Fig. 1. Fig. 3 is a cross section of the same taken on line 3—3 of Fig. 2.

In the drawings 5 designates a typical automobile frame carrying engine 6. At the forward end of the engine my starting device 7 is mounted on engine shaft 8.

Keyed rigidly on shaft 8 is a sleeve 9 carrying a drum 10 which carries on its inner periphery a series of inwardly sprung pressed pawls 11. Springs 12 are of sufficient strength to press the pawls inwardly when shaft 8 and drum 10 are stationary. But the rotation of the drum will cause pawls 11 to be thrown outwardly by centrifugal action against the inward effort of springs 12. Pawls 11 normally engage with ratchet teeth 13 in the periphery of member 14 which is loosely mounted on sleeve 9 so as to rotate thereon independently of the rotation of drum 10 or to remain stationary while the sleeve and drum are rotating in the direction indicated by the arrow in Fig. 3. Member 14 is provided with an outwardly extending flange 15 with ratchet teeth 16 on its periphery, these teeth facing in a direction opposite to that of teeth 13 and being engaged by a pawl 17 mounted on a stationary portion 18 of the automobile frame and preventing the rotation of member 14 in the direction indicated by the arrow in Fig. 4. By this means it will be seen that, should the engine tend to rotate in the direction indicated in Fig. 4, pawls 11 will transmit such rotation to member 14, but member 14 will be prevented from rotation by pawl 17. But when the engine rotates in the direction indicated in Fig. 3, immediately it has acquired a sufficient velocity of rotation, the pawls are thrown back into their pockets and out of engagement with teeth 18, leaving member 14 at rest and preventing pawls 11 from dragging over the teeth and causing unnecessary and disagreeable noise and wear.

Member 14 is provided with an inner periphery immediately under flange 15 and is there supplied with ratchet teeth 20. These ratchet teeth face in a direction opposite to that of teeth 13 and are engaged by a set of pawls 21 mounted on a sleeve 22, the arrangement being such that a rotation of sleeve 22 in the direction indicated in Fig. 3 will cause the rotation of member 14. 5
 10 Sleeve 22 is loosely mounted upon sleeve hub portion 14^b of member 14 and has a projecting arm 14^a through the medium of which it may be rotated. In the arrangement illustrated, I have shown a cable or other flexible 15 transmitting member 25 attached to arm 14^a and connected to a hand lever 26 located on the frame of the machine in a position convenient to the driver's seat. A pull rearwardly upon the lever 26 will cause the rotation of the various parts of my mechanism in the direction indicated in Fig. 3 and cause the engine to start its normal operation. A spring 27 returns arm 14^a and the connected mechanism to its original position. 20
 25 Pawls 11 are thrown out of engagement with ratchet teeth 13 and the engine rotates with only drum 10 revolving. Should a back-fire occur, pawl 17 prevents the driver from being injured; but pawl 17 is not in 30 continuous operation as it would be if it engaged directly with drum 10.
 From the foregoing it will be seen that the gist of my invention consists mainly in the provision of two members, one free and one 35 attached to the engine shaft, a ratchet connection between the two members which will rotate the engine member from the free member but which will be thrown out of engagement when the engine member begins 40 its own normal rotation, and a ratchet mechanism engaging with the free member to prevent its rotation in a rearward direction. The exact means used for rotating the free member is not particularly essential to the 45 invention as I consider it, changes of arrangement and design being possible in this regard without overstepping the bounds of my invention. An obvious change which may be desirable consists in making the device 50 operable by a foot pedal, the substitution of this device for the hand lever effecting no change in the invention.

Having described my invention, I claim.
 1. A device of the class described, comprising a shaft, a drum rigidly mounted on the shaft and having an overhanging rim, a plurality of pawls mounted in the rim and projecting from its inner periphery, spring means for pressing the pawls inwardly, a ratchet member loosely mounted on the drum and having ratchet teeth in its outer periphery adapted to be engaged by the pawls so as to transmit motion from the ratchet member to the drum in one direction, a second set of ratchet teeth on the ratchet member, a stationary pawl adapted to engage with the last named ratchet teeth and to thereby prevent the rotation of the ratchet member in the opposite direction, a rotatable sleeve loosely mounted on the ratchet member, pawls mounted on the sleeve, a third set of ratchet teeth on the ratchet member and adapted to be engaged by the last named pawls to transmit motion from the sleeve to the ratchet member in the first mentioned direction, and means for rotating the sleeve. 55

2. A device of the class described, comprising a shaft, a drum rigidly mounted on the shaft, a pawl mounted on the drum and projecting inwardly, a ratchet member mounted concentrically with the drum and having ratchet teeth in its outer periphery adapted to be engaged by the pawl on the drum so as to transmit motion from the ratchet member to the drum in one direction, another set of ratchet teeth on the ratchet member, a stationary pawl adapted to engage with the last named ratchet teeth and to thereby prevent the rotation of the ratchet member in the opposite direction, a rotatable sleeve concentrically mounted with the drum and ratchet member, ratchet connection between the sleeve and the ratchet member adapted to transmit motion from the sleeve to the ratchet member in the first mentioned direction, and means for rotating the sleeve. 90
 95

In witness that I claim, the foregoing I have hereunto subscribed my name this 28th day of December, 1910.

W. S. JOHNSON.
